VESSEL

Henry Jenett, Englewood, N. J., assignor to
Celanese Corporation of America, a corpora-
tion of Delaware

Application July 17, 1933, Serial No. 680,727

2 Claims. (Cl. 229—52)

This invention relates to drinking cups and like vessels and relates more particularly to cups intended for temporary use and which are provided with means for the reception of a removable handle.

An object of my invention is to provide means on cups or other vessels for the temporary reception of a ball or handle. Other objects of this invention will appear from the following detailed description.

Paper cups in the form of cones, frustum cones and analogous shapes intended to be used but once are widely used. These cups are usually provided with no handles and are therefore open to the objection that when containing very cold or hot liquids, they cause discomfiture to the hands when held. While cups provided with handles permanently attached thereto have been proposed in order to overcome this difficulty, such cups are open to the objection that they cannot be nested and therefore occupy a great amount of space when packed, transported or stored.

In accordance with my invention, I prepare cups or other vessels that are provided with means for the reception of a removable handle, bail or ear. Since such handle is intended to be inserted in the cup only immediately prior to its use, the cups may be nested when shipped or stored and therefore a large number of them may be packed in a relatively small package.

The means for the reception of the handle may be in the form of recesses, passageways, slots and the like formed on or in the side of the cup, and any suitable expedients may be employed for providing such means. For instance, in making the cup of paper or analogous material, the blank of which the cup is made may be made considerably longer than the circumference of the cup, and this excess of material may be employed by suitable scoring and folding to form the recess or passageway. Alternately the passageway may be formed of paper or other material which is not an integral part of the material of which the sides of the cup are made.

The cups or vessels may be made of suitable materials such as paper coated with waterproof material such as paraffin wax or other waxes or materials imparting impermeability to the same.

In a preferred form of my invention, however, I employ paper or other material which is coated with a layer of a composition comprising a derivative of cellulose, such as cellulose nitrate, and particularly organic derivatives of cellulose, such as cellulose acetate, cellulose formate, cellulose propionate and cellulose butyrate or other or-

ganic esters of cellulose or methyl cellulose, ethyl cellulose and benzyl cellulose and other cellulose ethers. This coating will preferably contain plasticizers for the derivative of cellulose, such as diethyl phthalate, dibutyl phthalate, diethyl tartrate, ethyl toluene sulfonamid, etc. This coating may be accomplished by brushing, spraying or dipping the paper in a solution of the derivative of cellulose and plasticizer in a volatile solvent such as acetone, methyl acetate or a mixture of methyl chloride and ethyl or methyl alcohol. Alternatively, foil, or sheet, or a layer of powder comprising the derivative of cellulose and plasticizer may be applied to the paper by means of heat and pressure.

While the paper from which the cups are formed may be coated on both sides, the coating of one side only, preferably the side forming the interior of the cup, is generally sufficient. The coating of the paper with a composition comprising a derivative of cellulose presents, among others, the advantage that the coating acts as an adhesive upon the application of heat and pressure, with the result that upon the assembly of the blank, the contiguous edges may be joined by the mere application of heat and pressure without the use of any extraneous adhesive.

Since the handle is intended to be used repeatedly, it may be formed of any desired material and of any decorative effect. The portions adapted to engage the passageway in the cup are preferably thin and therefore are preferably made of metal, while the handle proper may be formed of or coated with compositions comprising derivatives of cellulose and plasticizer having any desired color or decorative effect therein.

Reference is had to the accompanying drawing, which shows by way of illustration and without any limitation of the scope of this invention, one of the many forms of my invention, wherein

Fig. 1 is a perspective view of a form of my invention.

Fig. 2 is a perspective view of the handle.

Fig. 3 is a horizontal cross-section along the line 3—3 of Fig. 1, and

Fig. 4 is a plan view of a blank from which the side and recess of the cups shown in Fig. 1 is made.

Referring to Figs. 1, 3 and 4, the cup 10 shown therein has its side 11 and passageway 12 formed of one piece, the blank thereof being shown in Fig. 4. The blank comprises the portion 13 which is of a length of over twice the circumference of the cup to form sides of double thickness, 13a, 13b. Besides the portion 13, the blank comprises

a remaining portion which is scored and folded at the dotted lines 14 to form the passageway 12 in the cup 10 upon assembly.

The lower edges of the passageway 12 are cut 5 away as shown at 15 to facilitate the insertion of the members 4 of the handle 5, the upward passage of the members 4 being prevented by the rim 16 of the cup 10.

In the use of the cup shown, it will be understood that after these cups are formed they may be nested and therefore shipped in compact form. When a cup is to be used, it is removed from its package, and a handle 5 is temporarily attached by sliding the members 4 thereof through the 15 bottom of the passageway 12, the rim 16 of the cup acting as a stop. After the cup has been used, the handle 5 is removed and is ready for reuse.

It is to be understood that the foregoing detailed description is given merely by way of illustration and that many variations may be made therein without departing from the spirit of my invention.

Having described my invention, what I desire to secure by Letters Patent is:

1. A cup or vessel adapted to contain a liquid and having a side formed of a single sheet of material, a portion of said sheet being folded upon itself to form a passageway for the reception of a separable handle.

2. A cup or vessel adapted to contain a liquid and having a side formed of a single sheet of paper, a portion of said sheet being folded upon itself to form a passageway for the reception of a separable handle.

HENRY JENETT.
